(57) CLAIM

The ornamental design for a planter as shown and described.

DESCRIPTION

FIG. 1 is a front right perspective view of a first embodiment of a planter according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front right perspective view of a second embodiment of the planter; and,

FIG. 10 is a rear left perspective view thereof.

The broken lines in the drawings illustrate portions of the planter and form no part of the claimed design.

The dashed breakaway lines indicate a symbolic break and any portion of the article between the breakaway lines forms no part of the claimed design.
